11 Claims. (Cl. 333—24.2)

(Granted under Title 35, U.S. Code (1952), sec. 266)

This application is a continuation-in-part of copending application Serial No. 4,828, filed January 26, 1960, for Absorption Modulator Switch, now abandoned.

The invention described herein may be manufactured and used by or for the Government for governmental purposes without the payment to me of any royalty thereon.

This invention relates generally to a broadband absorption modulator-switch capable of providing very rapid switching of microwave energy.

Microwave devices used for switching or amplitude modulation of microwave energy preferably should have a low insertion loss in the normally "On" state and broadband operation. When the overall response of the device is independent of the frequency of the microwave energy which is selectively switched, the operation may be termed broadband.

Other desirable characteristics include a matched input impedance for all values of applied magnetic field, high isolation substantially independent of the magnitude of the applied magnetic field in the "Off" state, reciprocal switching and modulating properties, low strength magnetic control fields, and small physical size.

An object of this invention is to provide an absorption modulator switch which has all of the above-mentioned characteristics.

Another object of this invention is to provide a modulator switch having nearly constant electrical characteristics over a large X-band frequency range.

A further object is to furnish a reciprocal microwave switch which has a switching time of less than one microsecond.

Still another object of the present invention is to provide an absorption modulator microwave switch in which the switching action is independent both of the microwave input frequency and of the strength of the applied magnetic field.

An additional object is to provide a microwave switch having a reciprocal response.

According to this invention, a magnetized ferrite rod which is incorporated in the waveguide section is split longitudinally and a thin resistive film is placed between the split sections of the ferrite. When the ferrite is centrally located inside a standard rectangular waveguide excited in its fundamental TE_{01} mode, with the resistive film in the ferrite oriented perpendicular to the input electric field, the resistive film highly attenuates the orthogonal TE_{10} mode generated by the longitudinally magnetized ferrite rod. The attenuation of this orthogonal TE_{10} mode makes the occurrence of Faraday rotation impossible since the latter can exist only if the TE_{01} and the TE_{10} modes are present simultaneously. By the effective suppression of Faraday rotation in the present switch, nearly constant electrical characteristics over a very large X-band frequency range are achieved. The reciprocal switching of microwaves is another result of suppressing Faraday rotation. It should be understood that the term "reciprocal" is intended in its usual sense. It means that the electrical characteristics of the switch are independent of the direction of propagation of microwave energy, as well as the axial direction of the applied magnetic control field.

2

The specific nature of the invention, as well as other objects, uses and advantages thereof, will clearly appear from the following description and from the accompanying drawing, in which:

5 FIG. 1 is a sectional side view of the modulator switch of this invention.

FIG. 2 is an end view of the device of FIG. 1.

FIG. 3a is a sectional side view of one embodiment of the resistive film placed between split sections of the ferrite rod.

10 FIG. 3b is a sectional side view of a preferred embodiment of the resistive film.

FIG. 4 is a plot of the electrical characteristics of the absorption modulator switch of this invention.

FIG. 5 illustrates the ferrite rod with the various electric and magnetic fields shown therein.

FIG. 6 is a plot of coupling coefficient $-K'$ against the applied magnetic field H_0 .

FIGS. 1 and 2 illustrate the microwave modulator

20 switch 11 of this invention. Therein, a standard rectangular waveguide section 12 is excited in its fundamental TE_{01} mode. A microwave signal to be switched is applied to one end of waveguide 12, exciting it in the aforesaid mode. A ferrite rod 13 is located on the central axis of waveguide 12. The rod 13 is split in half through its longitudinal axis, forming the two sections 15 and 16 shown in FIG. 1. A resistive film 17, described in detail subsequently, is located between ferrite sections 15 and 16, and is supported by the opposed planar surfaces of sections 15 and 16.

25 A sleeve 19 of polystyrene foam or other suitable plastic supports rod 13 in a central position within waveguide 12 so that its longitudinal axis is concentric with the longitudinal axis of the waveguide. Resistive film 17 is thus placed along the waveguide axis in a plane

30 perpendicular to the input R.-F. electric field. The sleeve 19 also serves to insulate the rod 13 from waveguide section 12. The ends of ferrite rod 13 are tapered, respectively, as indicated at 24 and 25 in FIG. 1. Tapered ends 24 and 25 provide the impedance matching necessary

35 for broadband operation.

35 A solenoid coil 14 wrapped in convolutions around the outside of waveguide 12 selectively applies a D.-C. magnetic field H_0 , shown in FIG. 5, to ferrite rod 13. Coil 14 is connected by a control switch 18 to any suitable

40 source of electrical energy, such as battery 20 of FIG. 1. As set forth in more detail below, the state or condition of switch 11 is controlled by controlling the application of current from source 20 to coil 14. When current is

45 applied to coil 14, longitudinally magnetizing ferrite rod 13, the microwave switch 11 is in the "Off" state. When control switch 18 is open, as shown in FIG. 1, and no current is present in coil 14, microwave switch 11 is in

its "On" or transmitting state.

45 The operation of switch 11 may be explained in the following manner. In general, the internal R.-F. mag-

50 netic field $\vec{h}$ and the associated R.-F. flux density $\vec{b}$ in-

55duced by field $\vec{h}$ in a ferrite medium are related by a tensor

60 permeability $[\mu]$, expressed by $\vec{b} = [\mu] \vec{h}$. For an arbitrarily magnetized polycrystalline ferrite, this relationship may be stated in matrix form as

$$\begin{bmatrix} b_x \\ b_y \\ b_z \end{bmatrix} = \begin{bmatrix} \mu_{xx} & \mu_{xy} & \mu_{xz} \\ \mu_{yx} & \mu_{yy} & \mu_{yz} \\ \mu_{zx} & \mu_{zy} & \mu_{zz} \end{bmatrix} \begin{bmatrix} h_x \\ h_y \\ h_z \end{bmatrix} \quad (1)$$

65 The subscripts referring to the three mutually perpendicular axes x , y and z . From the above expression, it has

70 been shown that, in the case of a magnetized but unsatu-

rated ferrite at microwave frequencies, the permeability tensor $[\mu]$ reduces to

$$[\mu] = \begin{bmatrix} \mu & -jK & 0 \\ jK & \mu & 0 \\ 0 & 0 & \mu_z \end{bmatrix} \quad (2)$$

See, for example, G. T. Rado, "Electromagnetic Characterization of Ferromagnetic Media," Transactions of the IRE (PGAP), vol. AP-4, No. 3, pp. 512-525, July 1956. For the latter case, a static D.-C. magnetic field H_0 is applied along the z axis and μ_x , K and μ_z are the complex permeability components in the three mutually perpendicular directions. Expanding

$$\begin{bmatrix} b_x \\ b_y \\ b_z \end{bmatrix} = \begin{bmatrix} \mu & -jK & 0 \\ jK & \mu & 0 \\ 0 & 0 & \mu_z \end{bmatrix} \begin{bmatrix} h_x \\ h_y \\ h_z \end{bmatrix} \quad (3)$$

gives the following equations:

$$\begin{aligned} b_x &= \mu h_x - jK h_y \\ b_y &= jK h_x + \mu h_y \\ b_z &= \mu_z h_z \end{aligned} \quad (4)$$

It can be seen from the first two equations of (4) above that an applied R.-F. magnetic field h_x induces a component b_x of the R.-F. flux density b which is proportional to μ . Due to the precession of spinning electrons in the ferrite medium about the z axis, the magnetic field h_x also induces a component b_y in the y -direction proportional to K . Accordingly, ferrite rod 13 when magnetized by coil 14 transfers portions of the applied microwave energy from the original TE_{01} mode to a tightly coupled orthogonal TE_{10} mode. The latter mode corresponds to the flux density component b_y generated in the magnetized ferrite 13.

The operation of absorption modulator switch 11 depends in part upon variations of complex permeability component K with the static magnetic field H_0 . With a low-loss ferrite medium at microwave frequencies where field H_0 is well below magnetic saturation, the real portion $-K'$ of the complex quantity K to a first approximation is

$$-K' \approx \frac{4\pi M_0 \gamma}{\omega} \quad (5)$$

where M_0 is the magnetization of the medium in the z direction, γ is the gyromagnetic ratio for electrons equaling 2.8 megacycles per second per oersted, and ω is the angular frequency of the incident microwaves in radians per second. The variation of coupling coefficient $-K'$ with the external magnetic field is plotted in FIG. 6, in accordance with experimental results. Only the real component is shown, the imaginary part being small in comparison.

As seen from the curve in FIG. 6 and Equation 5 above, coefficient $-K'$ is zero when no external magnetic field is applied by coil 14. Since $\mu' = \mu'_z = 0.76$ for this case, μ' and μ'_z being, respectively, the real portions of μ and μ_z , ferrite rod 13 exhibits a scalar permeability. This scalar permeability of rod 13 of less than unity at X-band frequencies and with no applied field, as opposed to the tensor permeability $[\mu]$ of rod 13 when axially magnetized, is due to the gyromagnetic resonance of the electron spins in the internal crystalline anisotropy field of the ferrite. When it is desired to place switch 11 in its "On" state, control switch 18 is opened so that ferrite rod 13 is not magnetized. The incident microwave energy propagated in the TE_{01} mode has its electric field E_1 directed perpendicular to the plane of the resistive film 17, in the manner illustrated by FIG. 5. The input energy thus serves to apply an R.-F. magnetic field h_x of FIG. 5 to the ferrite rod 13. Since there is no field h_y in the y direction associated with the incident energy and since com-

ponent K is negligible with the ferrite unmagnetized (its major portion $K' = 0$), Equations 4 reduce to:

$$\begin{aligned} b_x &= \mu h_x \\ b_y &= 0 \\ b_z &= \mu_z h_z \end{aligned} \quad (6)$$

All of the input energy remains in the original TE_{01} mode, none being converted to the orthogonal TE_{10} mode. This follows since $b_y = 0$ above. The resistive film 17 acts as a polarization sensitive attenuator, sharply attenuating or damping the TE_{10} mode energy but having a negligible effect upon any microwaves in the original TE_{01} mode. While waves having an electric polarization in a plane parallel to resistive film 17 are dissipated thereby, the input electric field E_1 is perpendicular to the plane of resistive film 17. It therefore does not induce currents in film 17 and suffers substantially no loss in propagating through waveguide section 12. The switch 11 is effectively in its "On" state.

To turn the microwave switch 11 "Off", control switch 18 is closed so that coil 14 produces the D.-C. magnetic field H_0 within waveguide 12. H_0 is applied in the z direction, as seen in FIG. 5. Therefore, the ferrite 13 exhibits the tensor permeability $[\mu]$ discussed supra. FIG. 6 shows that for any substantial applied field greater than 10 oersteds, the coupling coefficient $-K'$ has an appreciable magnitude of 0.5 or more. Accordingly, permeability component K is no longer negligible, as was the case with switch 18 open. Now Equations 4 take the form

$$\begin{aligned} b_x &= \mu h_x \\ b_y &= jK h_x \\ b_z &= \mu_z h_z \end{aligned} \quad (7)$$

because the h_y component of the incident energy is zero, as before. FIG. 5 illustrates the conditions present in ferrite rod 13. The incident R.-F. magnetic field h_x induces the flux density b_x as before, and field h_x further induces a flux density b_y in the y direction within the ferrite medium 13 as shown by Equations 7. Flux density component b_y accounts for the microwave energy converted by ferrite rod 13 to the tightly coupled orthogonal TE_{10} mode. This energy converted by ferrite 13 has an electric polarization shown in FIG. 5 vector E_2 . It is seen that electric vector E_2 , perpendicular to b_y , is parallel to the plane of the resistive film 17. The TE_{10} wave associated with b_y induces currents within the resistive film 17 and is therefore immediately absorbed and dissipated within film 17. The end portion of ferrite rod 13 located at the input side of waveguide 12 receives the incident energy first and begins to generate the orthogonal TE_{10} mode. That portion of the incident microwave energy which the initially encountered section of ferrite rod 13 converts to the TE_{10} wave is substantially attenuated or damped as just described. The balance of the incident energy, which remains in the TE_{01} mode corresponding to the flux density component b_x of FIG. 5, is continuously and progressively attenuated as the signal propagates axially along rod 13, even though its electric polarization is perpendicular to resistive film 17. This can be explained by considering the conditions at a point farther along rod 13 as shown in FIG. 5 by axes X' and Y' . While the original R.-F. field of the incident energy was h_x at axes X and Y , it is reduced to a smaller strength h_x' as illustrated by FIG. 5. The microwave R.-F. field is reduced from h_x to h_x' because the b_y component of the original incident energy associated with h_x is dissipated in film 17 as heretofore described. But the small fraction of the original input signal which reaches axes X' and Y' contains the R.-F. field h_x' . The latter field again induces in the ferrite medium 13 two flux densities b_x' and b_y' , the energy converted to the polarization of b_y' being dissipated in resistive film 17. Therefore, by merely employing a ferrite rod 13 of sufficient length, substantially all of the applied energy is attenuated and switch 11 is "Off" whenever a D.-C. field H_0 is present.

The microwave switch 11 of this invention has electrical switching characteristics which are substantially independent of the microwave frequency and of the strength of control field H_0 . Since this switch does not rely in its operation upon the Faraday rotational effect, its insertion loss and electrical isolation do not critically depend upon the frequency of the incident energy or the control field magnitude, as has been true of prior ferrite switching devices which make use of the Faraday rotation phenomenon. With the microwave switch 11 it is merely necessary for the ferrite rod 13 to have sufficient length and cross-sectional area to produce the desired degree of isolation at the lowest operating frequency expected. The cross-sectional area must be large enough to concentrate the incident microwave energy in the ferrite medium at the 15 lowest frequencies. As the input frequency increases, progressively shorter lengths of the ferrite rod are required for a given degree of attenuation or damping. At higher frequencies, the ferrite rod 13 is more effective in converting the applied energy to the orthogonal TE_{10} mode. Therefore, by making the ferrite rod 13 long enough to isolate the lowest microwave frequency encountered, the rod has more than enough length at higher frequencies. In this manner, independence of the input frequency is obtained.

The present switch is also reciprocal in nature and operation. Reversing the direction of propagation or the direction of field H_0 has no effect upon generation of the b_y flux density of FIG. 5. In contrast, the conventional ferrite switches using Faraday rotation are inherently non-reciprocal.

FIG. 3a shows in detail one form of resistive film 17 in which a laminated construction is employed. There, film 17 consists of a dielectric film 21 coated with two films 22 and 23 of aquadag. Film 21 has a thickness of 0.0002 inch, while films 22 and 23 are 0.0004 inch thick. Aquadag films 22 and 23 consist of a colloidal suspension of graphite in water painted onto the opposite sides of dielectric film 21. Film 21 may be any thin dielectric material such as Mylar.

A preferred type of resistive film 17 is shown in detail in FIG. 3b. A very thin strip of high quality mica 26 serves as a base. Mica film 26 has a thickness of 0.0005 inch and should be selected for uniform thickness. A very thin layer 27 of a pure metal such as chromium is deposited by vaporization techniques upon film 26. The layer or film 27 has a thickness of 0.0001 inch. Since the pure metal is in the form of a very thin film, it has a high resistance. The metal film 27 is covered by a film 28 composed of a low loss dielectric serving as a protective coating to prevent oxidation of metal film 27. Film or layer 28 also has a thickness of 0.0001 inch.

The curves of FIG. 4 illustrate the electrical characteristics of particular modulator switches constructed in accordance with this invention. The solid curves 31 and 32 illustrate, respectively, the insertion loss in the "Off" state and the VSWR in the "On" state for a microwave switch with a laminated resistive film 17 such as shown in FIG. 3a when operated at an input frequency of 9250 mc. The switch 11 producing the response shown by curves 31 and 32 contains a split magnesium-manganese ferrite rod 13 having a height of 0.280 inch, a width of 0.300 inch, and a length of 4 inches including a one inch taper at each end for impedance matching (see FIGS. 1 and 2). This ferrite rod is supported by polystyrene foam insulation in a brass rectangular waveguide section having an 0.40 inch by 0.90 inch internal cross section. A switch so constructed provides nearly constant electrical characteristics over a frequency range from 7,500 megacycles to 10,500 megacycles. The zero field insertion loss in the normally "On" state is approximately 0.5 decibel and the isolation for the "Off" state exceeds 40 decibels, as shown by curve 31. The input voltage standing wave ratio is less than 1.2 for all values of applied magnetic field, and the switching time is less than one microsecond. A magnetic

field H_0 of less than 30 oersteds gives satisfactory control of the state of the switch.

Dotted curves 33 and 34 in FIG. 4 relate to another microwave switch according to this invention. This switch 5 employs a metallized mica resistive film as illustrated by FIG. 3b with a resistivity of 65 ohms per unit area. The ferrite rod has a height of 0.300 inch, a width of 0.320 inch, and a 4 inch length including $\frac{1}{8}$ inch tapers at both ends. The above switch gives an isolation well over 60 decibels at 9,250 mc., as shown by curve 33 for control fields of 30 oersteds or more. It has been found that this switch provides isolations greater than 60 decibels over a 2500 mc. bandwidth and as much as 55 db isolation was obtained over a 3500 mc. bandwidth.

Finally, when the resistivity of the attenuating resistive film is properly adjusted, nearly zero phase shift occurs at the desired input frequency. Thus, amplitude modulation without any phase modulation is possible with the absorption modulator switch of this invention.

It will be apparent that the embodiment shown is only exemplary and that various modifications can be made in construction and arrangement within the scope of the invention as defined in the appended claims.

I claim as my invention:

- 25 1. An absorption modulator switch having broadband characteristics, comprising: a section of rectangular waveguide, a coil mounted around the outside of said waveguide section for applying a longitudinal magnetic field within said waveguide section, a ferrite rod insulatingly supported within said waveguide section so that the longitudinal axes of said rod and said waveguide section are coaxial, said rod split longitudinally thereof forming two opposing sections, a resistive film lying wholly in a plane which is oriented parallel to the longer side walls of said 30 waveguide section and located between said two ferrite sections, and a control circuit for selectively applying current to said coil.
2. An absorption modulator switch as claimed in claim 1, wherein said resistive film comprises a thin film of dielectric with a coating of a suspension of minute graphite particles.
3. An absorption modulator switch as claimed in claim 1, wherein said resistive film comprises a base layer of mica having a thin coating of metal vapor deposited thereon.
4. A reciprocal absorption modulator switch having broadband characteristics, comprising: a rectangular waveguide excited in the fundamental TE_{01} mode, a coil around said waveguide for selectively applying a longitudinal magnetic field to said waveguide, a ferrite rod insulatingly supported within said waveguide for generating microwave energy in the TE_{10} mode, the longitudinal axis of said rod being coaxial with the longitudinal axis of said waveguide, said rod being longitudinally split so as 50 to form two halves, and a resistive film between said two halves for attenuating said TE_{10} mode energy said resistive film lying wholly in a single plane which is oriented parallel to the longer side walls of said waveguide.
5. A reciprocal switch as claimed in claim 4, wherein 55 said resistive film comprises a thin film of dielectric with a coating of a suspension of minute graphite particles.
6. A reciprocal switch as claimed in claim 4, wherein said resistive film comprises a base layer of mica having a thin coating of metal vapor deposited thereon.
7. A reciprocal microwave switch comprising a waveguide having a rectangular cross section, coil means mounted around said waveguide for producing an axial magnetic field, means mounted centrally within said waveguide for selectively switching incident microwave energy, said switching means comprising a ferrite rod split longitudinally into two sections along a plane which is oriented 60 parallel to the longer side walls of said waveguide and a resistive film positioned between said two sections, and control means for selectively energizing said coil means.

8. A reciprocal switch as claim in claim 7, wherein said resistive film comprises a thin film of dielectric with a coating of a suspension of minute graphite particles.

9. A reciprocal switch as claimed in claim 7, wherein said resistive film comprises a base layer of mica having a thin coating of metal vapor deposited thereon.

10. A reciprocal microwave switch comprising a rectangular waveguide excited in the TE_{01} mode, coil means around said waveguide for selectively applying a longitudinal magnetic field inside said waveguide, ferrite means mounted along the longitudinal axis of said waveguide for selectively switching microwave energy independently of the strength of said magnetic field, said ferrite means comprising a ferrite rod split in half and resistive attenuating means positioned perpendicular to the TE_{01} mode electric field and between the halves of said ferrite rod, and control means for selectively applying current to said coil means.

11. A microwave switch comprising: a rectangular wave guide; means for selectively producing an electromagnetic field within said wave guide; and means for reciprocally switching incident microwave energy within said wave guide; said switching means comprising a ferrite

rod split into two sections and a resistive film positioned perpendicular to the shorter walls of said rectangular wave guide said resistive film being positioned between said two sections of said ferrite rod.
